SEED GERMINATING TRAY

Louis V. Phelan, Wayland, Mass., assignor to
 Dennison Manufacturing Company, Framingham, Mass., a corporation of Massachusetts

Application May 1, 1941, Serial No. 391,428

1 Claim. (Cl. 47—37)

My invention relates to the germination of plant seeds, and includes among its objects and advantages the provision of an improved tray for growing seedlings for transplanting purposes.

An object of my invention is to provide a tray comprising waxed paper cut as a blank and scored along predetermined lines to facilitate bending of the blank into tray formation. The blank is provided with a system of interlocking slots and tabs which support the folded blank in a sturdy manner.

A further object is to provide a tray formed of a single piece of material bendable along predetermined lines, with the original blank having a tray bottom area of considerably greater width than the width of the tray and bendable in such manner as to provide a tray bottom having a channel formation facilitating circulation of water underneath the tray. The bottom of the tray is perforated for the passage of water and permits it to rise in the soil in the tray through capillary action.

Another object is to provide a tray which may be cut from sheet material and distributed to the trade in its original flat form, stacked or bundled in compact formation to facilitate handling and transportation, in addition to being so fashioned as to facilitate bending and interlocking of the parts by the user.

In the accompanying drawing:

Figure 1 is a perspective view illustrating a series of trays assembled in a watering box;

Figure 2 is a plan view of the blank from which the tray is folded;

Figure 3 is a cross sectional view of the tray;

Figure 4 is a fragmentary perspective view of the blank illustrating the manner in which the bottom area is bent to provide a water circulating channel contoured in the nature of an inverted V;

Figure 5 is a perspective view of an end portion of the tray illustrating the manner in which the locking tabs are interconnected; and

Figure 6 is a perspective view of the same end with the locking tabs pushed completely home.

In the embodiment selected to illustrate my invention, I make use of a waxed paper blank 10 which is generally rectangular in contour, as viewed in Figure 2. The material of the blank may comprise wax coated cardboard. Notches 11 are formed in the two ends of the blank, which notches are located intermediate the side edges of the blank to provide two ears 12 at each end of the blank. One ear upon each end is notched at 13 and additionally slit at 14 to provide a tab 15. These two ears 12 are located at diagonally

opposite corners of the blank. Each of the remaining two ears 12 is provided with a curved slot 16 extending generally in parallelism with the two side edges 17.

5 Three parallel score lines 18, 19 and 20 are formed longitudinally of the blank 10. The area 21 located between the score lines 18 and 20 constitutes the bottom portion of the tray, but this area is somewhat wider in the blank than the actual width of the tray formed through folding of the blank. The lines are equally spaced and the score lines 18 and 20 are located at the same distances from the side edges 17. The two areas 22 located between the respective score lines 18 and 20 and the side edges 17 define the side walls of the tray, with the ears 12 forming the end walls thereof. Score lines 23 define the lines of bend between the respective ears and the side walls of the blank. All the ears 12 are of the same widths as the side areas 22.

10 To form the tray from the blank 10, the blank is folded back upon itself along the score line 19, after which the two side areas 22 are folded upwardly along the score lines 18 and 20. The bottom area 21 and the side areas 22 then take the configuration of a W, as when viewing Figure 4. All four ears 12 are then bent inwardly along their respective score lines 23 and the tabs 15 are inserted in their respective slots 16, as in Figure 5, 15 with the result that a slight downward pressure on the ears 12 carrying the tabs 15 shift the latter into the positions of Figures 3 and 6. Since the edges 24 of the ears 12 constitute continuations of the edges 17, the top edges of the ears 12 lie flush with the top edges of the side walls of the tray when the blank is folded and the tabs interlocked in the manner of Figures 3 and 6.

20 Since the bottom area 21 in the original flat condition of the blank is considerably wider than the width of the erected tray, the tray bottom takes the configuration of Figure 3, which is in the form of an inverted V. Thus the tray rests on the edges 25 of the ears 12 and along narrow ridges 26 corresponding to the score lines 18 and 20. 25 It will be noted that the rounded corners 27 on the ears 12 provide a relatively large notch 28 in each end wall of the tray for the free circulation of water.

20 In operation, it is preferable to employ a watering box 29 into which a series of trays 30 is placed. These trays are somewhat shorter than the watering box 29 to provide an unoccupied compartment 31 into which the water may easily be poured. The trays 30 should have heights at least equally that of the watering box 29 so as

to facilitate proper exposure to the sun. At the same time, the side walls of the trays 30 fit in face to face engagement when in the watering box 29 as well as with respect to the side walls of the box. Thus the side walls are braced against sagging which might otherwise occur as an incident to the weight of the soil therein. In the bottom area 21 of the blank 10 is provided a series of perforations 32 which are located on the score line 19. In the tray condition of the blank, the perforations 19 extend along the apex of the bottom and facilitate the passage of water through the bottom to be taken into the soil through capillary action. This arrangement provides the ideal watering facilities for plants in that the moisture is applied from underneath rather than by pouring the water into the trays through the tops thereof.

The blanks 10 may be assembled and packaged in bundle formation for distribution to the trade. The score lines facilitate bending of the blanks and it is a relatively easy matter to bend the trays and interlock the end tabs. The ends of the bottom area 21 are rounded slightly at 33

so that the ears 12 will fit more closely to the edges when folded into position and thereby provide a soilproof relationship between the ends of the tray bottom and the end walls thereof.

Without further elaboration, the foregoing will so fully illustrate my invention that others may, by applying current knowledge, readily adapt the same for use under various conditions of service.

I claim:

10 A seed germinating tray comprising a blank foldable along predetermined lines to provide side walls and a bottom, said bottom being wider in the blank than in the tray and bendable to provide a raised bottom providing a water circulating channel underneath the tray, and interlocking means on said side walls for supporting the folded blank in tray formation and providing end walls, said interlocking means comprising extensions of said side walls projecting beyond the ends of the bottom wall and lying flatwise against the ends of the bottom, and said bottom being provided with bulging end edges with said end walls bending firmly thereagainst.

20 LOUIS V. PHELAN.
